UNITED STATES PATENT OFFICE.

CARL WALThER, OF CHEMNITZ, GERMANY, ASSIGNOR TO THE FIRM OF SCHUBERT & SALZER MASCHINENFABRIK AKTIENGESELLSCHAFT, OF CHEMNITZ, GERMANY.

EMBROIDERING-MACHINE.

1,175,492.

Specification of Letters Patent. Patented Mar. 14, 1916.

Application filed December 19, 1913. Serial No. 807,675.

To all whom it may concern:

Be it known that I, CARL WALThER, a citizen of the German Empire, residing at Chemnitz, in the Kingdom of Saxony, Germany, have invented certain new and useful Improvements in Embroidering-Machines; and I do hereby declare the following to be a full, clear, and exact description of the invention, such as will enable others skilled in the art to which it appertains to make and use the same.

My invention relates to improvements in embroidering machines and the like, and more particularly in the arrangement of the pantograph of embroidering machines by means of which the pattern to be embroidered is transmitted to the frame carrying the goods being embroidered so as to produce thereon the desired pattern.

The object of the improvements is to construct the means for fixing the pantograph in such a way, that the point of the pantograph is not pressed out of its proper position when fixing the pantograph, that the operative field of the pantograph is not limited by applying thereto the fixing means, that the friction of the pantograph is reduced to a minimum and the operation of the apparatus is easy, and that the pantograph can be fixed in a reliable way and is not loosened by operating the frame carrying the goods, putting thereon other goods, etc.

With this object in view my invention consists in providing special means for simultaneously fixing the pantograph against horizontal and vertical movements and providing means for independently fixing the pantograph against said movements.

By providing my improved fixing means the field of operation of the embroiderer is not interfered with, the pantograph is fixed in a reliable way, because the members to be fixed are subject only to strains acting in one direction, that is either to tension or to pressure, and the apparatus does not accidentally loosen itself.

For the purpose of explaining the invention several examples embodying the same have been shown in the accompanying drawings, in which the same letters of reference

have been used in all the views to indicate corresponding parts.

In said drawings Figure 1, is a side view 55 of a part of an embroidering machine and the pantograph provided with my improved fixing means, Fig. 2, is an enlarged plan view of the fixing means, Fig. 3, is a view of a modification of the fixing means, Fig. 60 4, is a side view of an embroidering machine provided with means for operating the fixing means from different parts of the machine, Fig. 5, is a plan view of the fixing means shown in Fig. 4. 65

In Figs. 1 and 2 I have shown my invention as embodied in a machine of known construction. As shown on brackets 2 secured to the frame 1 of the machine a pattern board 3 is mounted. The pantograph 70 consists of links 4, 5, 6 and 7 which are jointed to one another in the usual way. The link 4 extends to the pattern board 3 and it is provided with a handle 30 for operating the pantograph. The link 7 extends beyond the joint of the link 6 and it is connected with the frame 8 adapted to carry the goods being embroidered. At the joint of the links 5 and 6 the pantograph is mounted on a bracket 9 secured to the frame 80 1 of the machine.

The link 6 is in the form of a bell crank lever the arm 10 of which is jointed to a bar 11. To the link 5 a bar 12 is jointed. Where the bars 11 and 12 cross each other 85 a bracket 13 is secured to the frame of the machine the end of which carries a U-shaped member 14 pivoted to said bracket having a rocking but no shifting movement longitudinally of the bracket. On the bracket 13 90 a shaft 15 is mounted which is provided with two rollers 16 and 17. Adjacent to the opposite ends of the shaft 15 and in front thereof two studs 18 and 19 are provided on the bracket 13. 95

The ends of the member 14 are in the form of internally threaded eyes or nuts having screws 20 and 21 screwed therein, which screws are located coaxially of the studs 18 and 19. The screw 20 carries a 100 hand wheel 22. The bars 11 and 12 bear by gravity on the rollers 16 and 17, and they are guided at their sides by the studs 18 and 19 and the screws 20 and 21.

In the example shown in Figs. 1 and 2 the bars 11 and 12 are fixed or clamped in position by turning the hand wheel 22 to the right and thereby forcing the screw 20 in the direction toward the arm 13. As the screw is mounted on the member 14, and the latter carries at its opposite end the screw 21, the bars 11 and 12 which are engaged respectively between the screws 20 and 21 10 and the studs 18 and 19 are clamped. The bar 11 which is pivotally connected to the arm 10 of the bell crank lever 6, 10 is provided to lock the pantograph as against horizontal movement, while the bar 12 which is 15 jointed to the link 5 locks the pantograph as against vertical movement. Both bars are subject only to longitudinal strains and either to tension or to pressure, so that the pantograph is fixed by the clamping action 20 of the screws in a reliable way. The pantograph which has thus been clamped in position can not be shifted in any direction, and it can not be accidentally loosened.

In Fig. 3 I have shown a modification of 25 the clamping means. As shown also the screw 21 is provided with a hand wheel 22', and the hand wheel 22 effects clamping of the bar 11 only, while the bar 12 is clamped by the hand wheel 22' secured to the screw 30 21. The member 14 is rigidly secured to or made integral with the bracket 13. While the weight of the pantograph is increased by the means for fixing the same in position, it will readily be understood that this 35 increase can easily be reduced to a minimum or even made entirely ineffective by methods known in the art. For example, the bars may be made light by constructing the same of light material such as aluminum. Or the 40 weight may be balanced by counter-weights. By guiding the bars 11 and 12 on rollers the friction is reduced to a minimum, so that the operation of the pantograph is easy. While in the example shown in Fig. 3 the 45 hand wheels 22 and 22' are secured to the screws 20 and 21 respectively for direct operation of the latter, I wish it to be understood, that my invention is not limited to such means for direct operation of the 50 screws, and that suitable transmission gearings may be provided for operating the said screws from one or more suitable parts of the machine. An example of such means is shown in Figs. 4 and 5. As shown in the 55 said figures, all the parts for immediately acting on the pantograph are similar to those shown in Figs. 1 and 2. However, instead of the hand wheel 22 a sprocket wheel 25 is secured to the screw 20. At the same 60 height with the said sprocket wheel and at the opposite side of the embroidering machine a sprocket wheel 26 is mounted which is connected with the sprocket wheel 25 by a continuous rope 27. At the opposite ends 65 of the said rope chains are provided which

engage on the sprocket wheels 25 and 26. By moving the rope in one or the other direction the screw 20 can be screwed into or out of clamping engagement with the bar 11 so as to clamp or release the bars 11 and 12, as has been described with reference to 70 Figs. 1 and 2.

I claim herein as my invention:

1. In an embroidering machine, the combination with the movable fabric frame and 75 the pantograph for moving it, said pantograph including two pivotally connected members; of two elements, one pivotally connected to each of said members, and means to hold said elements against move- 80

2. In an embroidering machine, the combination with the movable fabric frame and the pantograph for moving it, said pantograph including two pivotally connected 85 members; of a bar pivotally connected to each member, said bars crossing one another, and means arranged at the crossing to clamp the bars.

3. In a machine of the class described the 90 combination with a movable frame for carrying the work, of a pantograph connected with the frame and having movements in two directions, two members connected to said pantograph and provided one for locking 95 the same against movement in one direction and the other one for locking the same against movement in the other direction, and common locking means for said members.

4. In a machine of the class described the combination with a movable frame for carrying the work, of a pantograph connected with the frame and having movements in two directions, two members connected to said pantograph and provided one for locking the same against movement in one direction and the other one for locking the same against movement in the other direction, locking means for said members, and operating means for said locking means extending over the length of the machine.

5. In a machine of the class described the combination with a movable frame for carrying the work, of a pantograph connected 115 with the frame and having movements in two directions, two bars connected to said pantograph and provided one for locking the same against movement in one direction and the other one for locking the same against movement in the other direction, and clamping means for said bars comprising relatively fixed abutments engaging said bars each at one side, a rocking member 120 engaging the bars at the opposite sides thereof, and a screw in said rocking member arranged for engagement with one of the bars.

6. In an embroidering machine, the combination with the pantograph thereof including two pivotally connected members;

100

110

115

120

125

130

of a bar pivotally connected to each member and movable with the pantograph, means to support the bars in crossed relation, an abutment adjacent each bar, and means to 5 clamp the bars against the abutments.

7. In an embroidering machine, the combination with the pantograph thereof including two pivotally connected members; of a bar pivotally connected to each member, a 10 bracket having guides thereon for said bars adjacent their crossing points, abutment studs on said brackets adjacent said crossing points, a U-shaped member pivoted on the bracket and movable abutments in said U- 15 shaped member opposite said studs.

8. In an embroidering machine the combination with the pantograph thereof including two pivotally connected members;

of a bar pivotally connected to each of said members, a bracket having a bar guide on its opposite sides, studs for the bracket substantially at the crossing point of the bars, a member on the bracket having an adjustable abutment in one end and a rotatable operating abutment in the other end, said 20 abutments coöperating with said studs to clamp the bars between them upon operating the operating abutment and endless means extending across the machine for rotating 25 said operating abutment.

In testimony whereof I hereunto affix my signature in the presence of two witnesses.

CARL WALTHER.
